CLAIM

The ornamental designs for an umbrella runner, as shown and described.

DESCRIPTION

FIG. 1 is an environmental perspective view of the umbrella runner, as illustrated in FIG. 2, in a position of use.

FIG. 2 is a top perspective view of the umbrella runner.

FIG. 3 is a bottom perspective view of the umbrella runner of FIG. 2;

FIG. 4 is a front view of the umbrella runner of FIG. 2;

FIG. 5 is a rear view of the umbrella runner of FIG. 2;

FIG. 6 is a right view of the umbrella runner of FIG. 2;

FIG. 7 is a left view of the umbrella runner of FIG. 2;

FIG. 8 is a top view of the umbrella runner of FIG. 2; and,

FIG. 9 is a bottom view of the umbrella runner of FIG. 2.

The broken lines are shown for the purpose of indicating environmental structure and portions of the umbrella runner and form no part of the claimed design.

1 Claim, 8 Drawing Sheets# US D738,610 S
